Application May 16, 1941, Serial No. 393,853

12 Claims. (Cl. 91—47)

This invention relates to a packaging machine and particularly to an adhesive applying device for a packaging machine.

The invention has for an object to provide a novel and improved packaging machine having an adhesive applying device of novel and improved construction, particularly adapted, among other uses, for applying adhesive to the interior surfaces of the closing flaps of a container in a manner such as to obtain the most efficient results in the sealing operation and so as to enable a tight and substantially sift-proof seal to be obtained.

With this general object in view and such others as may hereinafter appear, the invention consists in the packaging machine and in the various structures, arrangements and combinations of parts hereinafter described and particularly defined in the claims at the end of this specification.

In the drawings which illustrate the preferred embodiment of the invention, Fig. 1 is a side elevation of a sufficient portion of a packaging machine, embodying the adhesive applying device, to enable the present invention to be understood; Fig. 2 is a plan view, as viewed from the line 2—2 of Fig. 1, some of the parts being omitted for clearness of illustration; Fig. 3 is a plan view as viewed from the line 3—3 of Fig. 1, showing some of the parts which were omitted in Fig. 2; Fig. 4 is an enlarged detail view in front elevation showing the adhesive applying members and associated mechanism; Fig. 5 is a plan view of the mechanism shown in Fig. 4, as viewed from the line 5—5 thereof; Fig. 6 is a detail view showing the adhesive applying members in a different position of operation; Fig. 7 is an enlarged detail view in side elevation as viewed from the line 7—7 of Fig. 4; and Figs. 8 and 9 are views in side elevation of safety devices for controlling the operation of the adhesive applying members in the event that no container is present, as will be hereinafter more fully described.

In general, the present invention contemplates an improved packaging machine embodying a novel adhesive applying device particularly adapted among other purposes, to be used in the application of adhesive to the interior surfaces of the closing flaps of a container. In the preferred embodiment of the invention, the container is supported in a pocket mounted upon an endless chain arranged to be intermittently driven to present the container to the various instrumentalities of the packaging machine for

5 partially forming the top closure, applying adhesive to the interior surfaces of the partially formed closure, applying pressure to the closure to perform the sealing operation and thereafter folding the sealed closure down upon the container to complete the closing and sealing thereof. The instrumentalities for performing the closure and for subsequently pressing and folding the closure may comprise any of the 10 usual mechanisms now in use, the present invention being particularly directed to the adhesive applying mechanism.

In the illustrated embodiment of the invention, provision is made for applying adhesive to the 15 interior surfaces of an elongated top closure formed by folding outwardly two opposed portions of an open end container and then pressing together the remaining two opposite walls. In prior adhesive applying mechanisms employed for this purpose, the adhesive applying member 20 for insertion between the upstanding walls of the preformed closure was made in one piece and necessarily had to be made of a width substantially less than the full width of the elongated closure to permit entrance of the adhesive applying member. Consequently, portions of the closure did not receive adhesive, and as a result, 25 certain portions, particularly near the ends of the closure, were left unsealed, leaving openings through which finely divided or powdered materials being packaged might eventually escape during subsequent handling and during transportation of the package.

In accordance with the present invention, the 30 adhesive applying member is constructed to be contracted in width in order to facilitate the insertion thereof between the walls of the preformed closure, and for thereafter expanding the adhesive applying member after insertion into the closure in order to apply adhesive to the full 35 length of the interior surfaces of the closure forming flaps. In the preferred embodiment of the invention, provision is also made for applying pressure to the exterior surfaces of the closure 40 forming flaps so as to effect wiping of the adhesive from the applying member to the interior surfaces of the closure during the withdrawal of the applying member therefrom. Thus, when 45 pressure is subsequently applied to firmly press and seal the adjacent walls of the closure together at a subsequent station, a complete seal is effected at the mouth thereof.

Another feature of the present invention resides in the provision of safety mechanisms including detectors for detecting the presence or

absence of a container at or being advanced to the applying station arranged to control the movement of the adhesive applying members to prevent the transfer of adhesive from the supply roll to the applying members in the event a container is not being advanced into applying position, and to prevent the interposition of the applying members between the presser members in the event no container is present at the applying station.

Referring now to the drawings, the present adhesive applying mechanism is preferably embodied in a packaging machine such as a top closing machine in which provision is made for forming an elongated top closure upon the container prior to the arrival thereof at the adhesive applying station. The containers 10 are preferably supported in pockets 12, which may be mounted upon endless carrier chains 11 arranged to be intermittently moved to present the containers to the various stations in the top closing machine. The illustrated top closure is preferably formed by folding outwardly two opposed portions of an open end container and pressing together the remaining two opposite walls to provide an elongated closure for the mouth of the container having opposing upstanding walls 14, 16. Provision may also be made at such previous station for preforming the elongated closure in a manner such as to present the upper edges thereof spaced apart to facilitate entrance of the adhesive applying member therebetween, as will be described.

In the illustrated embodiment of the invention, the adhesive applying mechanism includes a pair of adhesive applying members or blades 18, 20 mounted to be capable of movement into engagement with an adhesive supply roller 22 whereby the members are provided with a film of adhesive, and then back into a position above and in operative relation to the closure to be provided with adhesive. As herein shown, the applying members 18, 20 are rockingly and slidingly mounted upon a rod 24 extending between supporting arms 26, 28, as best shown in Fig. 3. The arms 26, 28 are mounted fast upon a shaft 30 carried in bearings 32, 34 formed upon the ends of levers 36, 38. The levers 36, 38 are mounted fast upon a cross-shaft 40 journaled in the side frames 42, 43. A cam lever 44 also mounted fast upon the cross-shaft 40 is provided with a cam roll 46 arranged to cooperate with a cam 48 mounted fast upon a cam shaft 50 forming part of the packaging machine. Thus, a rocking movement of the blade supporting unit is provided to move the adhesive applying blades toward and from the supply roll 22, as illustrated in full and dotted lines in Fig. 3.

In order to control the movement of the adhesive applying unit so as to effect a wiping action of the blades 18, 20 against the supply roll 22, and to effect lowering and raising of the blades into and out of the elongated closure of a container presented in operative relation thereto, a second cam 52 is provided which cooperates with a cam roll 54 carried by a lever 56 pivotally mounted on the cross-shaft 40. The cam lever 56 is connected by a link 58 to an arm 60 formed integrally with the arm 26, as shown in Fig. 3, so as to form a four bar linkage operative to control the vertical movement of the adhesive applying unit during its rocking movement as effected by the cam 48, as above described. The cam 52 is designed so that in operation the adhesive applying blades 18, 20 are caused to fol-

low an upward wiping movement in engagement with the periphery of the supply roller 22.

As illustrated in Figs. 1 and 2, the adhesive supply roller 22 may form part of an adhesive supply mechanism of any usual or preferred form including a cooperating spreader roll 62. The co-operating rollers 22, 62 are continuously supplied with adhesive from a pipe 64 forming part of a recirculating system, the surplus adhesive being guided back to the source of supply through the funnel 66, as shown in Fig. 1. The rollers 22, 62 are geared together through cooperating gears 68, 70, one of which may be driven through connections (not shown) from the packaging machine.

In the operation of the device, when the adhesive applying unit is returned to the position shown in Fig. 1, above and in operative relation to the closure to which adhesive is to be applied, 20 the cam 52 through the four bar linkage described, operates to lower the adhesive applying blades 18, 20 between the walls 14, 16 of the elongated closure to transfer the adhesive thereto. Thereafter the blades 18, 20 are raised to their 25 starting position, above the closure, to again be rocked forward into engagement with the supply roll, as above described.

In accordance with the present invention, prior to the introduction of the applying blades 18, 20 between the walls of the closure, provision is made for contracting the blades so as to facilitate their insertion between the walls of the closure. As best shown in Fig. 3, the slidingly mounted blades 18, 20 are arranged to be moved longitudinally of 30 the rod 24 toward and away from each other through connections including links 72, 74, a bell crank 76 pivotally mounted upon and carried by the arm 28, and a three-armed lever 78 similarly pivotally mounted upon the arm 26. One arm 80 of the bell crank 76 is provided with a slot 82 arranged to receive a pin 84 carried by one arm 86 of the three-armed lever 78. A spring 89 extended between the arm 26 and the arm 86 is arranged to urge the applying blades 18, 20 away 35 from each other to their fully expanded position, as illustrated in dotted lines in Fig. 3. In order to contract the blades to their full line position shown in Fig. 3, provision is made for engaging an outwardly extended arm 90 of the three-armed 40 lever with an adjustable screw 92 carried in the end of one arm 94 of a cam lever 96 rockingly mounted on the cross-shaft 40. A cam 98 mounted upon the cam shaft 50 is arranged to cooperate with a cam roll 100 carried by the cam lever 55 96 to effect engagement of the screw 92 with the extended arm 90 when the blade unit is rocked into position to present the blades above the closure, and through the linkage above described the blades are contracted prior to being lowered 60 between the walls of the closure. Upon being lowered into the closure, the cam 98 operates to remove the screw 92 from engagement with the arm 90 whereupon the blades are again expanded by the spring 89 to the full length of the 65 closure, the outer edges of the blades being yieldingly urged against the ends of the closure by the spring 89. It will be observed that the blades are normally limited in their outward movement by engagement with the ends of the supporting 70 arms 26, 28 as shown in dotted lines in Fig. 3. However, when the blades are expanded within the closure they are naturally limited in their outward movement by the ends of the closure, as above described, thus assuring contact of the 75 walls of the closure with the blades and the ap-

plication of adhesive to the full length thereof irrespective of variations in the length of the closure upon successive containers presented to the applying mechanism.

Referring now to Figs. 4, 5 and 6, as illustrated therein, provision is made for rocking one of the blades 18 to an offset position with respect to its companion blades 20, prior to the contraction of the blades in order to prevent interference of one with the other during contraction, and in order to prevent adhesive from being wiped from one to the other as they overlap one another during such contraction. As herein shown, the blade 20 is directly attached to its hub 23 while the blade 18 is mounted to be capable of pivotal movement with relation to its hub 19. The hubs 19 and 23 are retained in longitudinal alignment with each other by the provision of an elongated tongue 102 extending from the hub 23 which is arranged to be received in a groove 104 formed in the hub 19. The pivotally mounted blade 18 is normally retained in longitudinal alignment with the blade 20 by a spring 106 when the blades are in their expanded position, as shown in Fig. 6. In order to rock the blade 18 upon its pivotal stud 108 as the blades are contracted, an arm 110 formed integrally with the pivotal connection 112, is provided with an upstanding pin 114 arranged to be engaged by the tongue 102 during the contracting movement to effect rocking of the blade 18 as above described, against the tension of the spring 106. It will be observed that the end of the tongue 102 is beveled to provide a cam action against the pin 114 at the start of the contracting movement. In operation, when the blades are lowered into the closure and are again expanded, the tongue 102 leaves the pin 114 to permit the blade 18 to again be brought back into alignment with its companion blade 20. It will be understood that the upper edges of the walls of the closure 14, 16 are sufficiently spaced, as indicated at the top of Fig. 2, to permit entrance of the blades in their offset condition.

Referring now to Figs. 4, 5 and 7, as above stated, provision is made for applying pressure against the exterior surfaces of the closure walls 14, 16 when the adhesive applying blades 18, 20 are inserted therebetween in order to effect transference of the adhesive from the blades to the interior surface of the closure during withdrawal of the blades therefrom. Simultaneously therewith, provision is also made for grasping the neck of the closure below the point of extension of the blades into the closure, as illustrated in Fig. 7, in order to prevent the mouth portion of the container from being drawn upwardly with the applying blades during their withdrawal movement. As herein shown, a pair of rubber faced presser members 120, 122 are yieldingly mounted in opposed pairs of supporting arms 124, 126 and 128, 130, respectively. The arms 124, 126 are mounted fast upon a cross-shaft 132 journaled in the side frames 42, 43. The cross-shaft 132 is arranged to be rocked through connections including a cam lever 134, also fast upon the cross-shaft 132 and which carries a cam roll 136 co-operating with a cam 138 fast on the cam shaft 50. The arms 128, 130 are similarly mounted upon a cross-shaft 140 arranged to be rocked in an opposing direction through connections including a cam 142, roller 144 and cam lever 146. The cams 138 and 142 are designed to rock the opposing presser members 120, 122 into cooper-

ative engagement with the exterior surfaces of the walls 14, 16 when the blades 18, 20 have been fully inserted into the closure. As shown in Fig. 7, the presser members 120, 122 are carried upon studs 148, 150 slidingly mounted in the opposing pairs of arms and are arranged to yield upon engagement with the closure by the provision of coil springs 152. The headed ends 154 of the studs limit the outward movement of the pressers to retain them in their supports when not in engagement with the closure.

It will be observed that the inner edges of the applying members 18, 20 are angularly arranged with respect to one another so that when the applying members are withdrawn from between the walls 14, 16 being pressed into engagement therewith a film of adhesive will be wiped across the angular spaced portion 121, formed between the members whereby to assure a continuous film of adhesive across the entire mouth of the container.

As best shown in Figs. 4 and 7, a pair of opposed gripper plates 155, 156 attached to similarly mounted arms 158, 160 and 162, 164 respectively, are arranged to yieldingly engage the neck portion of the container closure during the engagement of the pressers 120, 122 therewith. The arms 158, 160 are pivotally mounted upon the supporting arms 124, 126 respectively, and the arms 162, 164 are likewise carried upon the supporting arms 128, 130. The arms are yieldingly mounted to engage the neck of the container by springs 166 carried in sockets 168 formed in the pivotal arms, and which bear against offset plates 170 attached to the supporting arms, as clearly shown in Fig. 4. A stop bar 172 also carried by each supporting arm is arranged to limit the movement of the pivotally mounted gripper arms when the grippers are not in engagement with the neck of the closure. With this construction, it will be seen that the elongated closure flaps are yieldingly retained in their normal position while the presser members 120, 122 bear against the exterior surfaces of the walls thereof whereby to prevent distortion of the closure during the withdrawal of the applying blades 18, 20.

The safety mechanisms for controlling the operation of the adhesive applying blades in the event that a container is absent from any of the pockets 12 will now be described. In the operation of the machine, the blade unit is arranged to be rocked to present the blades, in their normally expanded condition, against the adhesive supply roll 22, during the time in which a new container is being advanced into operative position to be provided with adhesive. In the preferred embodiment of the invention, provision is made for preventing the transfer of adhesive from the supply roll to the blades in the event that a container is absent from the pocket at the station immediately prior to the adhesive applying station or during its travel from such prior station to the latter so as to prevent an excessive accumulation of adhesive upon the applying blades. As best shown in Fig. 9, in such an event, provision is made for rocking the blades upon their pivot 24 so as to avoid engagement of the blades with the supply roll 22, as shown in dotted lines in Fig. 9.

Referring to Figs. 1, 2 and 3, the rocking of the blades is effected through connections including an arm 174 formed integrally with the blade hub 23, link 176, a bell crank 178 pivotally mounted on the shaft 30 and a link 180 connected

to one arm 182 of a bell crank rockingly mounted on the cross-shaft 40. The second arm 184 of the bell crank is arranged to be engaged by the longer member 186 of two latch members 186, 188 pivotally mounted at 190 in a bracket 192 attached to the side frame 42. As illustrated in Figs. 1 and 2, the longer latch member 186 is operatively connected to a detecting mechanism including a feeler bar 194 arranged to detect the presence or absence of a container in the pocket being advanced to the applying station. As shown in Fig. 1 the feeler bar 194 is mounted fast upon a rocker shaft 196 and is arranged to be rocked counterclockwise into the path of the oncoming container by a spring 198, and to be rocked clockwise by the engagement of the container with the bar, which as illustrated in Fig. 1 extends from the prior station to a point adjacent but not engaging the container at the applying station. The rocker shaft 196 is journaled in bearings 200 attached to the machine frame, and the connections between the rocker shaft and the latch member 186 include an arm 202 fast on the rocker shaft 196, link 204, bell crank 206, and a link 208 swivelly connected to an arm 210 formed integrally with the latch member 186. The link 208 is slidingly mounted in its swivelled connection and a collar 212 fast on the link is arranged to engage the swivel to positively urge the latch 186 in a clockwise direction and into the path of the arm 184 when there is no container present in the pocket. A spring 214 interposed between the opposite side of the swivel and a second collar 216 also fast on the link 208 is arranged to yieldingly rock the latch in a counterclockwise direction when there is a container present in the pocket.

In the normal operation of the device, when there is a container present in the pocket, and the latch 186 is rocked up out of the path of the arm 184, the latter will engage the second or shorter latch member 188, as shown in full lines in Fig. 9. Thus, normally the adhesive applying blades 18, 20 are retained in their substantially vertical position so as to permit the blades to engage the supply roll 22 as described. However, when the arm 184 is engaged by the latch 186, as shown in dotted lines in Fig. 9, indicating the absence of a container from the pocket, the blades will be rocked as shown to avoid the supply roll 22. The arm 184 may be urged in a counterclockwise direction, viewing Fig. 9, against the latch members 186 or 188 by a spring 218. A roller 220 carried by the arm 221 of the bell crank 178 is arranged to engage a stationary resetting cam 222 on the return stroke of the blade supporting unit in order to rock the arm 184 into a position to be engaged by the latch 186 during the next cycle of operation, in the event a container is absent during such cycle.

Referring now particularly to Fig. 8, a second safety device is provided for controlling the operation of the blades 18, 20 to prevent lowering of the blades between the presser members 120, 122 in the event that a container is absent from the pocket at the applying station, so as to prevent the transfer of adhesive onto the presser members. The second safety device includes the shorter latch member 188 and a cam operated feeler or detector arm 224 arranged to be rocked into and out of the path of the container at the applying station. The feeler arm 224 is mounted upon a vertical rod 226 which is arranged to be rocked through connections from a cam 228 in-

cluding a cooperating cam roller 230 carried by one arm 232 of a three-armed lever pivotally mounted on the safety latch pivot 190, and a link 234 connecting a second arm 236 of the three-armed lever to an arm 238 mounted fast on the vertical rod 226. It will be observed that ball and socket connections 240 are employed throughout the device wherever the parts partake of an oscillatory as well as a lateral movement. A coil spring 242 carried in a socket formed in the third arm 244 of the three-armed lever bears against the upper surface of the bracket 192 and urges the three-armed lever in a counterclockwise direction, viewing Figs. 1 and 8, to cause the roller 230 to follow its cam 228. Thus the detector arm 224 is rocked into and out of the path of the container at the applying station during the operation of the machine. The shorter latch member 188 is connected to the second arm 236 of the three-armed lever by a spring 246 connected to an arm 248 formed integrally with the latch member 188. A set screw 250 adjustably carried by the arm 236 is arranged to bear against the arm 248, as clearly shown in Figs. 1 and 8, the latter being urged thereagainst by the spring 246. Thus, in operation, the latch member 188 will tend to follow the cam operated lever during its rocking movement to present the feeler arm 224 into and out of the path of the container at the applying station.

In the normal operation of the second safety device, when there is a container present in the pocket 12 at the applying station, the movement of the feeler arm 224 into the path of the container will be arrested upon engagement therewith, thus holding the three-armed lever and the latch member 188 in the position shown in Figs. 1 and 8, against the tension of the spring 242, the cam roll 230 being held away from its cam 228 during this time. Thus, normally the arm 184 will be engaged by the latch member 188, as illustrated in full lines in Fig. 8, which will maintain the blades 18, 20 in their substantially vertical position as they are lowered into the closure as previously described. However, in the event that a container is absent at the applying station, the roller 230 will follow its cam 228 and the latch member 188 will be rocked counterclockwise out of the path of the arm 184, as shown in dotted lines in Fig. 8. Thus, the blades 18, 20 will be permitted to rock counterclockwise on their pivot 24, as shown in dotted lines in Fig. 8, and when the blade unit is lowered, as above described, the blades will assume a position to the right of the presser members 120, 122 so as to avoid engagement of the presser members against the adhesively coated surface of the applying blades. As illustrated in Fig. 8, the rocking movement of the blades is limited by the engagement of the roller 220 with the inclined surface 252 of the stationary cam 222 and the latter also effects resetting of the arm 184 to be again engaged by the latch members 186, 188, upon the forward movement of the blade supporting unit as above described.

From the above description it will be observed that the present construction of the adhesive applying device is particularly adapted for the application of adhesive upon the interior surfaces of the container closing flaps and enables the application of adhesive to the full length of such interior surfaces whereby to permit a completely sealed closure to be provided across the entire mouth of the container to enable the production

of a substantially sift-proof container. In the preferred and illustrated embodiment of the invention adhesive is applied to the interior surface of only one of the closing flaps, the opposing surface being pressed into engagement with the adhesive coated surface to produce a firm seal. It will be understood, however, that the interior surfaces of the entire mouth of the container may be provided with adhesive if desired. It will also be understood that the present mechanism may be used in the application of adhesive to other types of closures. It will also be observed that the novel control mechanism embodied in the present adhesive applying device for controlling the operation of the adhesive applying members enables the packaging machine to be operated with maximum efficiency.

While the preferred embodiment of the invention has been herein illustrated and described, it will be understood that the invention may be embodied in other forms within the scope of the following claims.

Having thus described the invention, what is claimed is:

1. In a packaging machine, in combination, means for supporting a container having extended closure forming portions, a pair of adhesive applying members movable into and from engagement with the interior surfaces of the walls of said closure forming portions to perform the applying operation, means for contracting said members to facilitate insertion within said walls, and means for expanding said members after insertion whereby to permit the application of adhesive to the desired portions of the interior surfaces of said closure forming portions.

2. In a packaging machine, in combination, means for supporting a container having extended closure forming portions, a pair of adhesive applying members movable into and from engagement with the interior surfaces of the walls of said closure forming portions to perform the applying operation, means for contracting said members to facilitate insertion within said walls, and means for yieldingly expanding said members after insertion whereby to permit the application of adhesive to the desired length of the interior surfaces of said closure forming portions.

3. In a packaging machine, in combination, means for supporting a container having an elongated closure, a pair of adhesive applying members movable into and out of engagement with the interior surfaces of the walls of said closure to perform the applying operation, means for contracting said members to facilitate insertion within said walls, and means for yieldingly expanding said members after insertion whereby to permit the application of adhesive to the interior surfaces of said elongated closure, said members being limited in their yielding expansive movement by engagement with the ends of said elongated closure.

4. In a packaging machine, in combination, means for supporting a container having extended closure forming portions, contractible adhesive applying means movable into and from a position within the walls of said closure forming portions to perform the applying operation, means for contracting said means to facilitate insertion within said walls, means for expanding said means after insertion into engagement with the ends of said closure forming portions whereby to permit the application of adhesive to substantially the full length of the interior surfaces thereof, and means for pressing the flaps into

engagement with said adhesive applying member whereby to effect transference of the adhesive from the applying means to said interior surfaces during withdrawal of the adhesive applying means.

5. In a packaging machine, in combination, means for supporting a container having an elongated closure, a pair of adhesive applying members movable into and from the interior of said closure to perform the applying operation, means for longitudinally contracting said members to facilitate insertion within said walls, means for longitudinally expanding said members after insertion whereby to permit the application of adhesive to substantially the full length of the interior surfaces of said closure, and means for pressing at least one wall of the closure into engagement with said adhesive applying members whereby to effect transference of the adhesive from the applying members to the interior surface thereof during withdrawal of the adhesive applying members.

6. In a packaging machine, in combination, means for supporting a container having an elongated closure, contractible adhesive applying means movable into and from a position within said closure to perform the adhesive applying operation, means for contracting said adhesive applying means to facilitate insertion within said closure, means for expanding said means after insertion whereby to permit the application of adhesive to substantially the full length of the interior surfaces of said elongated closure, and means for gripping the neck portion of said closure whereby to prevent adherence of the closure to said adhesive applying means during the withdrawal thereof from within the closure.

7. In a packaging machine, in combination, means for supporting a container having an elongated closure, contractible adhesive applying means movable into and from a position within said closure to perform the adhesive applying operation, means for contracting said adhesive applying means to facilitate insertion within the closure, means for expanding said means after insertion whereby to permit the application of adhesive to substantially the full length of the interior surfaces of said elongated closure, means for pressing the walls of said closure into engagement with said adhesive applying means during withdrawal of the latter, and means for gripping the neck of the closure whereby to prevent adherence of the closure to the adhesive applying means during such withdrawal movement.

8. In a packaging machine, in combination, means for supporting a container having an extended closure, contractible adhesive applying means, an adhesive supply roll, means for moving the applying means into cooperative engagement with the supply roll to receive a film of adhesive, means for moving the adhesive applying means into and out of engagement with the interior surfaces of said closure to perform the applying operation, means for contracting said means to facilitate insertion into said closure, means for expanding said means after insertion whereby to permit application of adhesive to substantially the full length of the closure, and control means for preventing the engagement of said applying means with said supply roll in the event of the absence of a container from said supporting means.

9. In a packaging machine, in combination,

means for supporting a container having an elongated closure, contractible adhesive applying means, means for moving the applying means into and out of engagement with the interior surfaces of the walls of said closure, means for pressing said closure into engagement with said adhesive applying means during withdrawal of the latter, means for contracting said means to facilitate insertion between the closure, means for expanding said means after insertion whereby to permit the application of adhesive to substantially the full length of the interior surfaces of said elongated closure, and control means for deflecting said adhesive applying means out of the path of said pressing means in the event that a container is absent from said supporting means.

10. In a packaging machine, in combination, container supporting means for supporting a container having a closure, an adhesive applying mechanism comprising adhesive supply means, and an adhesive applying member moveable into and from engagement with said supply means and adapted to receive adhesive from said supply means, and mechanical control means for holding said adhesive applying member out of engagement with said adhesive supply means in the event of the absence of a container from operative position.

11. In a packaging machine, in combination, means for supporting a container having a closure, adhesive applying means comprising adhesive supply means and an adhesive applying member movable into and out of engagement with said adhesive supply means and adapted to receive adhesive from said supply means, means for moving the adhesive applying member into and from the closure, and mechanical control means for holding the adhesive applying member out of engagement with said supply means in the event of the absence of a container from operative position.

12. In a packaging machine, in combination, means for supporting a container having a closure, an adhesive applying member, means for moving the adhesive applying member into and from the closure, means for pressing together the walls of the closure into engagement with said adhesive applying member during withdrawal of the latter from the closure, and control means for moving said adhesive applying member out of the path of said presser members in the event of the absence of a container from operative position.

GEORGE A. ROBINSON.
